APPARATUS FOR MAKING BAGS

Adolph Potdevin, Garden City, Long Island, N. Y.,
assignor to Potdevin Machine Company, Brook-
lyn, N. Y., a corporation of New York

Original application September 6, 1933, Serial No.
688,279. Divided and this application November
20, 1934, Serial No. 753,820

13 Claims. (CL 93—13)

This invention relates to improvements in apparatus for making bags and is particularly well adapted for making bags from material such as cellulose acetate, cellulose hydrate, glassine, and like materials, as distinguished from paper.

5 In the accompanying drawing:

Fig. 1 is a plan view somewhat diagrammatic of an apparatus constituting one embodiment of my invention;

10 Fig. 2 is a side elevation of the apparatus of Fig. 1; and

Figs. 3, 4 and 5 show the bag in the various stages of its manufacture.

Referring to the drawing in detail: The material is taken from a supply roll 1 and the web, designated 2, is led about a roller 3 and past plates 4 which are adapted to fold the opposed edges of the web over toward each other upon the main body of the web to form flanges 5 at opposite sides 20 of the web.

The web then passes between rollers 6 by which the flanges are turned outwardly again so that the web is once more flat.

25 In its flattened condition the web passes notch-
ing mechanism comprising notchers 7 and 8 at each side of the web and adapted to notch the web as shown at 9 and 10. The notchers 7 and 8 are mounted on the same shafts.

The notchers 7 and 8 are held to their support-
30 ing shaft 11 by screws 12, so that the spacing of the notches 9 and 10 lengthwise of the web 2 may be varied to suit different conditions.

The web still in opened-up or flat condition then passes about rollers 13 and 14 to bring the 35 flanges 5 of the web into contact with adhesive-applying discs 15.

These adhesive-applying discs as seen from Fig. 2 are segmental so that alternate flanges 5 have the adhesive stripes 16 applied thereto. In other words, the flanges to one side of one pair of opposed notches 9 will have adhesive applied thereto, while the adjacent flanges at the other side of these notches will be left plain.

The discs 15 are made adjustable as shown at 45 17 to vary the length of their periphery.

The web next passes plates 18 which are adapted to turn the flanges 5 which have had adhesive applied thereto inwardly again, so that these flanges will be pasted down to the body of the 50 web 2.

To insure that only alternate flanges will be turned inwardly again, I provide rocking fingers 19 intermediate the roller 14 and plates 18, these fingers which engage the web along the line of the fold which provides the flanges 5 being so timed

that the leading end of a pair of pasted flanges will be directed above the end of the plates 18, while the leading end of the succeeding pair of flanges will be directed below these plates.

The web next passes between rollers 20, past 5 cutting off mechanism 21 and between rollers 22 and 23.

The cutting off mechanism comprises a rotary cutter bar 24 driven in the direction of the arrow on Fig. 1 cooperating with a fixed member 25. 10 The function of this cutting off mechanism is to sever the main body of the web transversely, across opposed notches 10 but an appreciable distance to one side (to the right as viewed in Fig. 1) of the center of these notches so as to leave a relatively long flap designated 26 in Fig. 1 on the trailing edge of the cut off portion and a relatively short flap 27 at the leading edge of the adjacent section of material.

Each length of material, therefore, is approximately double the length of the finished bag and as shown in Fig. 1 is composed of what I shall term two panels designated 28 and 29, respectively, the flanges 5 of the panel 28 being turned inwardly over upon the body of the web 2 to which they are pasted, while the flanges 5 on the panel 30 are in an opened up condition.

The length of material shown at the left in Fig. 1 passes from the rollers 23 to forwarding and creasing rollers 30 and 31. The roller 30 is provided with a creaser blade 32 and the roller 31 with a gripper 33 controlled by a cam 34. The setting and timing of these two rollers 30 and 31 are such that the creaser blade 32 engages the web substantially along the line 35 of Fig. 1 to force the web downwardly with respect to the roller 31 so that the gripping finger 33 may function to grip the material. Continued rotation of the roller 31 draws the material around with this face of a roller 35 lying adjacent thereto to fold the two panels lengthwise of the web, over upon each other as illustrated in Fig. 3.

In this condition the inner faces of the flanges 5 of the panel 29 are contacted with gluing discs 45 36 which apply adhesive thereto as shown at 37 in Fig. 4.

The folded material then passes between rollers 38 and finally between a pair of superposed belts 39 which fold the flanges 5 of panel 29 over upon 50 the panel 28 as shown in Fig. 5 which completes the bag.

While I have illustrated and described one embodiment of my invention I do not wish to be limited to the precise structure herein shown and 55

described as obviously various modifications and changes may be made therein without departing from the spirit and scope of my invention.

This application is a division of my copending application Serial No. 688,279 filed September 6, 1933.

What I claim is:—

1. A bag making machine comprising in combination web-advancing means and a pair of rotary notchers at opposite sides of the machine rotatable about axes parallel to the direction of travel of the web, the notchers of each pair being offset with respect to each other so as to provide pairs of notches in the opposed edges of the web, the notches of each pair being half a bag length apart.
2. A bag making machine comprising in combination web-advancing means, creasing means for providing longitudinal creases adjacent the edges and a pair of rotary notchers at opposite sides of the machine rotatable about axes parallel to the direction of travel of the web, the notchers of each pair being offset with respect to each other so as to provide pairs of notches in the opposed edges of the web, 25 the opposed edges of the web in line with said creases the notches of each pair being half a bag length apart.
3. A bag making machine comprising in combination web-advancing means, a pair of rotary notchers at opposite sides of the machine rotatable about axes parallel to the direction of travel of the web, the notchers of each pair being offset with respect to each other so as to provide pairs of notches in the opposed edges of the web, the notches of each pair being half a bag length apart, and cutting off mechanism for severing the web adjacent alternate pairs of notches into sections substantially twice the length of bag 35 lengths.
4. A bag making machine comprising in combination web-advancing means, a pair of rotary notchers at opposite sides of the machine driven about axes parallel to the direction of travel of the web, the notchers of each pair being offset with respect to each other so as to provide pairs of notches in the opposed edges of the web at substantially a half bag length apart, and means for adjusting the setting of the notchers to vary the distance between notches thereby to accommodate the machine to bags of different lengths.
5. A bag making machine comprising in combination web-advancing means, a pair of rotary notchers at opposite sides of the machine driven about axes parallel to the direction of travel of the web, the notchers of each pair being offset with respect to each other so as to provide pairs of notches in the opposed edges of the web at substantially a half bag length apart, means for adjusting the setting of the notchers to vary the distance between notches thereby to accommodate the machine to bags of different lengths, and cutting off mechanism for severing the web into sections having opposed notches substantially midway of its ends.
6. A bag making machine comprising in combination web-advancing means, means in the path of the advancing web for turning the edges of the web inwardly to provide side flanges and then to restore the web to flat condition again, 70 paste applying means for applying spaced stripes of adhesive to the upper face of said side flanges, pairs of notchers at opposite sides of the machine for notching the edges of the flat web at predetermined intervals to provide panels in the web the flanges of alternate panels being pasted,
- means following the notchers for refolding the edges of pasted alternate flanges over on the body portion of the web, and cutting-off mechanism for severing the web transversely adjacent the leading end of each flanged panel, to provide a length of web substantially twice a bag length with a pair of opposed notches substantially midway of the length.
7. A bag making machine comprising in combination means for applying paste at intervals along the opposite edges of a traveling web, notchers for notching the opposite edges of the web at each end of the paste areas, folding mechanism for turning the pasted edges of the web inwardly upon the main portion of the web on further advance of the web, cutting-off mechanism for severing the web transversely at the leading end of each pasted area, rotary advancing or forwarding means for advancing the severed lengths, and clamping mechanism carried thereby for gripping a severed length midway of its length so that the severed length will be deflected out of its previous path of travel and be drawn between two rollers to fold the length transversely to bring the portions of the length at each side of the transverse fold into parallelism.
8. A bag making machine comprising in combination means for applying paste at intervals along the opposite edges of a traveling web, notchers for notching the opposite edges of the web at each end of the paste areas to provide opposed alternately pasted and unpasted flanges folding mechanism for turning the pasted flanges inwardly upon the main portion of the web on further advance of the web, cutting- 35 off mechanism for severing the web transversely at the leading end of each pasted area, rotary advancing or forwarding means for advancing the severed lengths, clamping mechanism carried thereby for gripping a severed length midway of its length so that the severed length will be deflected out of its previous path of travel and be drawn between two rollers to fold the length transversely to form two superimposed panels, paste applying means for applying paste to the unpasted flanges, and means for folding the last-mentioned flanges over on the outside of the opposed panel to paste the same thereto.
9. A bag making machine comprising in combination web-advancing means, pairs of notchers mounted on shafts at opposite sides of the machine for notching the edges of the web at pre-determined intervals to provide flanged panels in the web which are to eventually form the walls of the bag, the notchers of each pair being adjustable circumferentially on their supporting shaft relatively to each other to vary the spacing of the notches in the web, cutting off mechanism for severing the web transversely adjacent alternate pairs of opposed notches.
10. A bag making machine comprising in combination web-advancing means, pairs of notchers mounted on shafts at opposite sides of the machine for notching the edges of the web at pre-determined intervals to provide flanged panels in the web which are to eventually form the walls of the bag, the notchers of each pair being adjustable circumferentially on their supporting shaft relatively to each other to vary the spacing of the notches in the web, cutting off mechanism for severing the web transversely adjacent alternate pairs of opposed notches and rotary means adapted to grip the length of web substantially midway of its length so that on continued advance of the web length the same will be folded 75

along a transverse line to bring the two halves into parallelism.

11. A bag making machine comprising in combination web advancing means, pairs of notchers at opposite sides of the machine for notching the edges of the web at predetermined intervals to provide two adjacent panels having flanges along their sides, folding means in the path of travel of the web for folding over the side flanges of 10 one panel, means preceding said folding means for directing the flanges of one panel through said folding means and for directing the flanges of the succeeding panel outside of said folding means thereby to fold over the flanges of alternate panels.
12. A bag making machine comprising in combination web advancing means, pairs of notchers at opposite sides of the machine for notching the edges of the web at predetermined intervals 20 to provide two adjacent panels having flanges along their sides, folding means in the path of travel of the web for folding over the side flanges of one panel, rocking fingers preceding said folding means for directing the flanges of one panel

through said folding means and for directing the flanges of the succeeding panel outside of said folding means thereby to fold over the flanges of alternate panels.

13. A bag making machine comprising in combination web advancing means, pairs of notchers at opposite sides of the machine for notching the edges of the web at predetermined intervals to provide two adjacent panels having flanges along their sides, folding means in the path of travel 10 of the web for folding over the side flanges of one panel, rocking fingers preceding said folding means for directing the flanges of one panel through said folding means and for directing the flanges of the succeeding panel outside of said 15 folding means thereby to fold over the flanges of alternate panels and rotary means adapted to grip the length of web substantially midway of its length so that on continued advance of the web length the same will be folded along a transverse line to bring the two halves into parallelism.

ADOLPH POTDEVIN.
